CLAIM

The ornamental design of the temperature controller for soldering irons, as shown and described.

DESCRIPTION

FIG. 1 is a top plan view showing my new design;
FIG. 2 is a bottom plan view showing my new design;
FIG. 3 is a front elevational view showing my new design;
FIG. 4 is a back elevational view showing my new design;
FIG. 5 is an elevational view showing one side of my new design;
FIG. 6 is an elevational view showing the other side of my new design;
FIG. 7 is a perspective view showing my new design; and,
FIG. 8 is a perspective view showing my new design in use.
The broken line showing is for illustrative purposes only and forms no part of the claimed design.
